UNITED STATES PATENT OFFICE.

JOHN CHARLES SNELLING, OF CHISWICK, LONDON, ENGLAND.

CONSTRUCTION OF REINFORCED-CONCRETE SHIPS.

1,301,013.

Specification of Letters Patent. Patented Apr. 15, 1919.

Application filed November 21, 1918. Serial No. 263,620.

To all whom it may concern:

Be it known that I, JOHN CHARLES SNELLING, a subject of His Majesty the King of England, and resident of Chiswick, in the 5 county of London, Kingdom of England, have invented certain new and useful Improvements in the Construction of Reinforced-Concrete Ships, of which the following is a specification.

10 This invention relates to an improved method of applying concrete and steel in the construction of reinforced concrete vessels of all types, so that no centering or false-work is required thereby greatly reducing 15 the cost of construction over present methods and the risk attendant on the removal of such centering or false-work.

Although the present method may be applied to all types of construction of skeleton 20 framework it has been found by experience that it is best suited to the special form of construction hereinafter described.

According to the present invention the vessel is built around a suitable metallic 25 framework to the outside of which pairs of sheets of expanded or perforated metal are suitably connected, concrete being filled in between the sheets so as to form the shell or part of the shell of the vessel. The keel of 30 the concrete vessel so formed is provided with a protective metallic plate extending from the top of the stem to the stern where the plate is widened to carry the propeller shaft bearings and afterward carried upward and branched laterally and rearwardly 35 so as to afford reinforcing and strengthening members for the stern and the sides of the vessel adjacent thereto, the plate being also connected by rivets or other suitable 40 means to the longitudinal and central reinforcing keel member.

The steel members of the metallic framework used as reinforcing members in the 45 keel are first laid in position on the building blocks. Interconnected and fixed to these at suitable intervals are placed the steel members, which are to form with the concrete, the strong frames or ribs, these members being, before fixing, given their correct curves. 50 Between these and connected thereto are placed the rods which form the horizontal members such as those forming the gunwale, inwale, sheer strake or other part of the ship's framework. When all such members 55 are in place the complete skeleton of the vessel is then ready for the skin reinforce-

ment, which consists of two or more sheets of perforated or expanded metal which are preferably maintained apart by distance pieces suitably connected to the metallic 60 members of the skeleton framework, the space between the perforated or expanded metal sheets being subsequently filled in with concrete to form the shell of the ship. As the entire operation of filling in the concrete 65 is visible during the entire operation there is less danger of voids or empty spaces occurring and the reinforcing steelwork being fixed there can be no displacement thereof. Further according to the present invention 70 vessels can be much more rapidly built than heretofore and the use of permanent core boxes or molds in the double bottoms or other hollow parts besides being much more rapid, eliminates all risk of the concrete being 75 displaced by the withdrawal of temporary coreboxes or molds. The reinforcing steelwork may be disposed in the most advantageous position and its complete covering by the concrete is assured. 80

I will describe with reference to the accompanying drawings a method of constructing concrete ships or vessels in accordance with the present invention but I do not limit myself to the precise construction described and illustrated:—

Figure 1 is a plan of a framework for use in constructing a small boat or vessel as for example a barge in accordance with the present invention. 90

Fig. 2 is a mid-ship section of Fig. 1.

Fig. 3 is a section drawn to an enlarged scale on the line 3—3 Fig. 4.

Fig. 4 is an enlarged section showing one form of keel-part. 95

Figs. 5 and 5^a show a mid-ship section of a double bottom type of vessel in accordance with this invention.

Fig. 6 is a longitudinal section on the line 6—6 Fig. 5^a. 100

Figs. 7, 8 and 9 are detail sectional views on the lines 7—7; 8—8; 9—9 Figs. 5 and 5^a, respectively, these views being drawn to an enlarged scale, and Fig. 9 showing in perspective the formation of the vertical and horizontal ribs or frames. 105

Fig. 10 is a perspective view of part of the outer skin as preferred for use in small ships.

Fig. 11 is a plan view of part of the double bottom showing the core boxes. 110

Figs. 12, 13 and 14 are respectively a side

view, an end view looking on the stem, and a cross section through the keel of a modified construction in accordance with the present invention.

- 5 The same reference numerals wherever repeated indicate the same parts.

Referring to the drawing, 1 indicates the longitudinal and transverse frame or skeleton members of the vessel which members 10 are formed of metallic rods and on the outside thereof are fixed spaced sheets 2, 3 (Fig. 2) of perforated or expanded steel or other suitable metal, the mesh generally used being that known as three-quarter inch. The 15 sheets 2, 3 of expanded metal pass outside of the longitudinal and cross members 1 on one side, the sheets 3 being located between the longitudinal and cross members 1 (see Fig. 3), and the sheets, in like manner, extend 20 downward and outside the bottom members 4 and outside the members 1 on the other side of the vessel thus inclosing the framework and so forming an uninterrupted hollow body of channel or other suitable 25 section having open mesh work sides and bottom. The space between the two sheets 2, 3 is regulated to requirement by suitable distance pieces 5 or pads preferably of concrete and of the shape shown in cross section. The inner sheet 3 of expanded 30 metal is then firmly fixed to the frame members 1 and 4, by wire bindings 6, clips or other suitable devices and the outer sheet 2 is separately fixed to the members 1 and 4 35 by wires 7 or other suitable devices. The sheets 2 may be bound or connected to the members 1 by a common binding device such as the wire 8, if so desired, (see Fig. 3).

In Fig. 4 the central bottom longitudinal 40 member 4 embedded in the upper part of the keel is shown as surrounded by a stirrup or binding piece 21 of expanded metal which stirrup is connected by wire 22 or other suitable device to the expanded metal sheet 3.

45 A similar stirrup construction is shown in Fig. 9. In working, the lowest stave or width of perforated or expanded metal is first fixed, that is both the inner and outer sheets and the intervening space between them is then filled in with suitable concrete 50 23 well rammed around the skeleton. The view obtained through the meshes of the perforated or expanded metal enables the operator to see that all voids or empty or 55 partially empty spaces are completely filled. As soon as the space is filled, a coat 24 of fine concrete of suitable composition is applied to the inner side of the expanded metal sheet 3, and a coat 25, to the outer side of 60 the expanded metal sheet 2, such fine concrete applied by hand as in plastering, or in other suitable manner, and sufficient force being applied to insure a dense coating and to thoroughly incorporate these coats with 65 the concrete between the expanded metal

through the meshes, thus very completely inclosing the whole. While these coats are being applied the next stave or width of expanded metal is fixed and the filling is proceeded with as before so that the whole 70 operation is continuous until the vessel is finished. It will thus be seen that by the present method, as there is no centering or falsework to remove, the building is greatly facilitated and can be continued night and 75 day until the vessel is completed. It is intended that all strong frames and other necessary members be filled in with concrete as the work proceeds thus rendering the whole homogeneous. 80

A further feature of the invention provides for vessels constructed as above but having double bottoms or other hollow parts. A double bottom construction according to this further feature is shown in Fig. 5 85 wherein 9 are the longitudinal and vertical rods of the shell and 17 and 18 the inner and outer bottom metallic rods, these rods being preferably placed at suitable positions so as to retain the sheets 10, 11 of expanded metal, 90 which are both arranged outside the rods, in the desired position. In this construction the longitudinal rods 9 are connected where desired as by cross rods 12, the sheets 10 and 11 of expanded metal being fixed outside the rods by wires, with or without distance pieces 14. It will thus be seen that the rods 12 and the inner shaped transverse rods 15 having the expanded metal sheets 10, 11 arranged around them as shown together with the concrete between the sheets, 95 form longitudinal and vertical strengthening frames 16, or ribs. The lower longitudinal are in two sets, an upper set 17 and a lower set 18. The reason for placing 100 both sheets of expanded metal outside the rods is that the concrete shall be absolutely continuous and unbroken, thereby being in the best form to take the compressive stresses. This only applies to the outer shell of concrete more particularly shown in Fig. 9. In forming the double bottoms with the rods 17 and 18 I provide light coreboxes 19 or forms which are placed in position where required with bent up sheets 20 of expanded 110 metal placed between them and the inside sheet of expanded metal and extending up the sides of the coreboxes which are fixed as by wires to the sheets of expanded metal of the adjacent shell parts. This construction 115 allows of the formation of suitable concrete strengthening webs 26 between the outer shell and inner shell of the double bottom. As and when the outer skin concrete is being applied the spaces between the sheets 120 are also filled in and reinforcement and concrete is then applied to form the top of the double bottom. This concrete, forming as it does the lower floor of the vessel, is finished off smooth as required. It will be seen 125 130

that by the use of these permanent core boxes or molds the work can proceed without waiting for the concrete to harden as they do not require to be withdrawn.

5 In the modification shown in Figs. 12, 13 and 14, the keel structure of the ship comprises a metal plate 27, butt or otherwise jointed at intervals along its length and extending up the stem of the ship. The plate 10 passes under the ship to the stern and is bent upward to form the stern post 28 which is continued in an aft and upward direction so as to form a suitable reinforcement for the upwardly and rearwardly extending 15 curved concrete stern portion of the ship. The plate is preferably widened at 29 where the propeller shaft indicated by 30 is designed to pass through and to this widened part a suitable boss 31 or bosses or bearings 20 are attached to carry the propeller shaft. The stern post 28 formed by the upwardly bent plate is provided with two or more laterally projecting ribs 32—33 which may be welded or otherwise secured to the stern 25 post. The metal plate thus carries three or more upwardly projecting prongs 32—33—34 or projections some 32—33 of which are lateral projections and at least one 34 of which is a rearwardly and upwardly extending projection, the latter projection being formed by the plate 27. Means are also provided for securing the attachments for the rudder.

The longitudinal central metallic rod 4 or other suitable metallic member of any desired thickness is placed at a suitable distance above the keel plate 27 and extends along the keel only or along the keel and up the stem or partly up the stem and if desired also the stern, the said rod 4 being connected at intervals by split rivets 35, one end 36 of which is riveted to the keel plate while the split ends 37—38 of the rivets are bent around the longitudinal rod 4, the two 40 combined forming the complete keel reinforcement members. The lateral rods 1, forming the transverse members of the skeleton frame-work may be connected to the longitudinal rod 4 by bending the ends 45 of the transverse rods 1 around the longitudinal rod 4, as shown in Fig. 14, or by any other suitable means. The longitudinal rod 4 is preferably bent as at 39 (Fig. 12) downward at the stern end so as to grip the 50 concrete, and the stern end 40 of the keel plate 27 is folded or turned around the rod 41 which forms the curved reinforcing stern member. Sheets 2, 3 of expanded metal are placed outside the longitudinal and transverse rods 1 and 4 respectively and between these sheets distance pieces 5 are arranged at suitable intervals apart both longitudinally and transversely, the space between the expanded metal sheets being thereafter 55 filled in with concrete.

Stirrup or binding pieces 42 or lengths of expanded metal are placed above the central longitudinal rod 4 and these stirrup pieces are connected by wire bending 43 or other suitable means to the lateral rods or metallic 70 ribs. The outer sheet 3 of expanded metal may be bulged or enlarged as at 44 to form a hollow space 45 at each rivet and along the keel plate so as to form a continuous solid keel throughout the ship's length and 75 may be connected between the rivets and the keel plate as shown at 46. The rivets 35 preferably pass through the inner sheet 2 of expanded metal. The outer sheet 3 of expanded metal thus forms a hollow openwork 80 casing which partly or if desired wholly surrounds each rivet and provides a suitable enlargement for the reception of the concrete so that the latter when applied or filled in between the sheets fills up the enlargement and entirely surrounds and incloses the rivet on all sides thereby preventing access of water between the keel plate and up between the concrete and the body 85 of the rivet. 90

After the concrete is filled in a finishing coat of fine suitable concrete is applied to each side of the filled in concrete, thus providing a plane surface without projections which are liable to crack or chip off in the 95 course of time.

The construction of keel hereinbefore described provides for the combination of an outside protective plate 27 or other suitable metallic section forming a protection against 100 the chipping of the concrete forming the stem and keel of the vessel and also itself taking its part in the reinforcing of these members in conjunction with the rod or rods inside the concrete the rods and concrete being connected together in a manner which presents the least possible area for water to act on the rods embedded in the concrete. It also provides a secure method of attaching the stern bearing or bearings 105 and alining the same during construction, and allows the vibrations of the propeller to the absorbed over a large area of reinforcing metal and concrete. Further the metal inclining toward the stern forms a 110 solid support for the rudder attachments and affords a ready means of alining this with the propeller or propellers while the vessel is being built. 115

Where watertight bulkheads, sub-divisions or floors are required the method of procedure is as for the vessel's outer skin and such bulkheads, sub-divisions or floors are completed at the same time, the essential feature being that the concrete is filled in 120 between two sheets of perforated or expanded metal. Obviously one advantage of the present method of construction is that while the exterior surface concrete of the vessel may be treated in a manner to keep 125 130

out water the interior surface concrete may be treated to resist the action of such cargo as may be carried.

Where insulated vessels or parts thereof are required the above method of light core-boxes or molds is extended so that the sides, bulkheads and floors are partly hollow thus forming dead air spaces whereby the interior of the vessel or portions thereof can be kept isolated for the purpose or purposes required.

The core boxes or molds need only be constructed of materials sufficiently strong to resist the ramming of the concrete between or on top of them and they may be of straw board, wood, or light metal either with plane surfaces, or ribbed, or corrugated for strength and according to the shape or size required; if desired they may be suitably interconnected so that the whole double bottom or parts thereof may be filled with water or other liquid for ballasting purposes; or they may be constructed of such materials as galvanized, tinned iron or other metal so as to form complete tanks or compartments suitable for the carrying of such liquids which would, if in direct contact with the concrete forming the structure do harm thereto.

30. Claims—

1. A reinforced concrete wall, comprising a frame or skeleton formed of adjacent longitudinal and transverse joined rods, sheets of perforated or expanded metal

lodged between the longitudinal and transverse rods, other sheets of perforated or expanded metal spaced from the first-named sheets, means connecting the second-named sheets to the rods, a filling of concrete between the first and second named sheets, and a surfacing of concrete embedding the sheets and the rods.

2. A concrete vessel having walls formed of spaced associated sheets of perforated or expanded metal, a filling of concrete between the sheets, a longitudinal rod having connections with the inner perforated sheet, and a stirrup piece of perforated or expanded metal passed around the rod.

3. In a concrete vessel, two or more expanded metal sheets in associated spaced relation, a filling of concrete between the sheets to constitute walls of the structure, a keel for the vessel, and a longitudinal central rod embedded in the keel and having downwardly projecting end portion.

4. In a concrete vessel, a series of longitudinal rods and transverse rods connected together, a filling of concrete around the rods to constitute the walls of the structure and a keel for the vessel, a longitudinal central rod embedded in the keel and connected to the transverse rods, a bottom plate for the keel, and a series of vertical members connected to the longitudinal rod and to said plate and spaced apart along the rod and embedded in the concrete.

JOHN CHARLES SNELLING.
